GOLF PRACTICE MAT OR THE LIKE

Mitchell G. Rosengarten, Philadelphia, Pa.

Application April 22, 1937, Serial No. 138,284

5 Claims. (Cl. 273—33)

My invention relates to golf-practice apparatus and the like, and especially to a mat from which golf-missiles can be played or driven. The invention also involves a novel combination of a mat 5 and a coacting missile-disc. For convenience, I use the word "driving" in a broad way to express the playing of a golf missile with any golf club or the like, without regard to the strict technicalities of golf parlance as to the particular club or implement used, or the force of the stroke: e. g., as including equally the very strongest strokes with a driver and the very lightest shot. I aim to provide a mat that will simulate as closely as possible the conditions of ordinary outdoor golf 10 on a regular golf course.

In ordinary golf, some strokes are made from a "tee" resting on bare ground; but more are made without any tee, from the greensward or fairway: i. e., with the ball lying in grass or on earth that 15 is rather yielding if touched or struck by the club. In some places where golf shots are practiced, ordinary cocoa mats (like doormats) are used to simulate grass; but such mats do not last well under the severe punishment of continual use; 20 do not really approach actual playing conditions very closely; and offer some danger of catching the club on a hard downward stroke and snapping it off, or injuring the wrist of the player. For practice with light cardboard missile-discs, mats 25 and tee supports are disclosed in my Patent No. 2,011,014 of August 13, 1935 and in my application Serial Number 15,550 filed April 10, 1935 which approximate the conditions of driving from 30 a tee, but do not correspond so well to shots from the greensward or fairway.

I have found that the conditions of ordinary outdoor shots from the fairway can be rather closely approximated by using a mat surfaced with bristles of suitable stiffness and length set 35 close together in a base which is somewhat yielding vertically. A material that answers very well for the facing is commercially available, consisting of the clothing used for carding machines in the textile industry. As a means of mounting the 40 facing to yield downward resiliently, I prefer to back the facing with a moderately resilient locally yielding pad, such as a thickness of fairly stiff, elastic sponge rubber. Such a mat may be used for driving ordinary golf balls; or for golf practice balls or missiles of any ordinary or preferred 45 type, such as the cotton ball sometimes used for indoor practice; and especially with cardboard missile-discs such as shown in my Patent Nos. 1,980,701, granted November 13, 1934 and 50 2,011,014, granted August 13, 1935. With such a

cardboard disc, the bristle wires serve to keep it upright without the use of a tee device or other holding means, and release it easily and naturally when it is struck.

Various other features and advantages of my 5 invention will appear from the following description of a species or form of embodiment, and from my drawing. All features shown or described are, indeed, of my invention, so far as 10 novel over the prior art.

In the drawing, Fig. I is a tilted or perspective view of one form of mat constructed in accordance with my invention, with a missile disc thereon ready for driving.

Figs. II and III are fragmentary sectional views, 15 taken as indicated by the lines and arrows II—II and III—III in Fig. I.

Figs. I, II and III show a mat comprising a facing 5 surfaced with upstanding wire bristles 6 set in a fabric base 7, which is backed with a 20 sheet of sponge rubber 8. The facing 5 and backing 8 are shown mounted in a frame 10 which may be of any desired shape and of any suitable material and construction, sheet metal 25 being preferred. The frame 10 is shown fairly wide and bevelled outward, with a gentle slope from the top surface of the facing 5 down to the floor all around, where it joins a back plate 11 that underlies the backing 8. It may be made of a substantially rectangular metal sheet, by bending 30 its margins inward after cutting away pieces at the corners. In Figs. II and III, an outer width of the inturned margins is shown bent down as at 12, so as to rest on the back plate 11 and engage the edges of the sheets 7 and 8. The 35 abutting surfaces of these sheets 7 and 8 are preferably secured together, as by rubber cement 13, and the back of the sheet 8 may be similarly secured to the plate 11, as by rubber cement indicated at 14. As shown in Fig. II, the wires 6 are 40 arranged or bent to slope slightly in the intended direction of driving, which is indicated by the arrows in Figs. I and II. The arrow 15 in Fig. I is intended to be painted or otherwise marked on the frame 10, so that the proper direction for 45 driving will always be obtruded on the attention of the player. At the rear end of the frame 10,—speaking with reference to the arrow 15,—a flange 16 projects inward over the tops of the 50 wires 6, which are slightly displaced downward. This flange 16 may be formed by a double fold of the sheet metal forming this side of the frame, above the downturned portion 12. The underside 55 of the back plate 11 may have a sheet or pad of

felt 17 cemented to it, to prevent the mat from slipping on the floor or scratching it.

Fig. I shows a cardboard missile-disc 20 (such as mentioned above) stuck in the mat in convenient position for driving; and in Figs. II and III, the outlines of such a missile-disc are indicated in dot and dash lines. The upstanding bristle wires 6 hold the disc 20 securely, by engagement of the disc margin amongst them, or by impalement of the margin on some of the wires, or in both these ways. The proper engagement of the cardboard disc 20 with the bristle wires 6 occurs automatically: all the player has to do is to press the disc edge firmly against the bristle surface of the mat, and then release the disc when he feels that he has forced it into the mat somewhat. The disc edge impales itself firmly on such wires 6 as it encounters end-on, and elastically deflects other wires 6 slightly, the wires 6 being resiliently flexible relative to the general plane of the mat. The player then plays or drives the disc 20 just as if it were a golf-ball lying on the fairway, or on a tee. The disc 20 releases itself easily from the ends of the bristles 6, which slope diagonally upward in the direction of the disc flight, as shown in Fig. II the release of the missile disc 20 is facilitated by the downward displacement of the facing 5 by the club and the lateral flexure of the bristles 6, both of which also avoid injury of facing and bristles by the club. If desired, of course, a tee clip such as shown in my Patent No. 2,011,014, granted August 13, 1935, or in my application Serial Number 15,550, filed April 10, 1935, could be used in the mat with a missile disc 20; but in general it is unnecessary.

When a golf ball or any ordinary form of golf practice missile is used, it is merely laid or thrown on the surface of the mat, as on a fair-way, without any attempt to press or force it down on the bristles 6, as described above in the case of the cardboard disc 20.

For any type of missile that might be used on it, from an ordinary golf ball to a cardboard disc, my mat affords conditions closely approximating those on the ordinary fairway: i. e., when a club strikes or scrapes over the mat, the bristles 6 bend down before it with a yielding cushion effect, like the turf of a fairway. Like the earth of a fairway, also, the resilient backing 8 under the card cloth or similar facing 5 yields locally to cushion the stroke and let the club pass more easily,—thus minimizing wear on the card cloth. In other words, the facing 5 yields downward under the pressure of the club, in addition to the lateral yielding or flexure of the wires 6; but the bristles return spontaneously to erect, even-surfaced condition. Provided the stroke is made with the bristles 6 as shown in Fig. II (and not against them or cross-wise), it has been found impossible to "catch" the club in the bristles 6, even with a stroke that has a somewhat exaggerated downward component. With a cocoa mat, such catching of the club sometimes happens,—resulting in a broken stick, or an injured wrist for the player. With an outward-bevelled metal-surfaced frame 10, it is also practically impossible to catch and break the club against the frame by an ill-aimed stroke,—unless, perhaps, the lower edge of the club-head should hit squarely against the angle-bend between the top surface of the frame and the bottom plate 11, which is very unlikely. The edges of the facing 5 and backing 8 are effectively protected by the frame 10, whose top edge is almost even with the

ends of the wires in Figs. II and III, though a trifle lower.

As already stated, the construction of ordinary card-clothing answers very well for the facing 5. Such card-clothing commonly comprises a stout, 5 flexible base 7 with fairly short bristle wires 6 fixed therein and projecting a certain uniform distance therefrom, parallel with one another. The base 7 may be of rubber, leather, or stout textile fabric: I prefer textile fabric, which may 10 advantageously be saturated with rubber, which is afterward vulcanized to leave the rubber elastic but firm. The wires 6 are preferably fairly stiff, resiliently flexible, fine steel wires such as generally used in card cloth, and set rather close together. Fine wires 6 projecting about a quarter of an inch from the base and set about thirty-three thousandths to one twentieth of an inch apart answer very well, particularly with a cardboard disc 20 about thirty-nine thousandths of 20 an inch thick. In the drawing, the size and spacing of the wires 6 is of course exaggerated for the sake of clearness of illustration. Commonly, pairs of adjacent wires 6 of card cloth are united behind the base 7, so that they are in effect like 25 staples driven through the base from behind. In card cloth, the wires 6 are customarily bent slightly all in one direction, as shown in Fig. II, which is advantageous for my purpose. The lateral flexure of the wires 6 seems to be partly due 30 to their own resiliency, and partly yielding in the mat. The rubber saturation of the mat minimizes internal wear amongst its threads due to this. One commercial grade of card clothing which I have used with good results is #28 CWC 35 of American Card Clothing Co.

For the elastic backing 8, I may use sheet sponge rubber about a half inch thick, preferably fairly stiff and resilient rather than very soft. A commercial grade which has given good results is 40 4075 black sponge rubber of Lee Tire and Rubber Co.

Having thus described my invention, I claim:

1. Game apparatus comprising in combination a plain cardboard missile-disc, adapted to be 45 propelled by a stroke of a golf club against its edge, and a driving mat comprising a facing mounted to yield resiliently downward under a stroke of a club and surfaced with upstanding bristle wires resiliently flexible relative to the 50 facing and of such length and stiffness and so spaced as to impale and receive amongst them the margin of the plain cardboard missile disc, when it is pushed edgewise against the facing, so that the facing and its bristles hold the disc upright to receive the stroke of the club, yet temporarily yield downward and laterally under such stroke, thereby avoiding injury of the facing and releasing the disc more easily.

2. A golfer's driving mat comprising a facing 60 composed of a flexible base surfaced with bristle wires upstanding free of lateral support above said base, and resiliently flexible relative thereto, so that they yield laterally under a golf club stroke at a missile on the mat, and means for 65 mounting said facing to yield resiliently downward under such a golf club stroke, all so that the bristle wires and facing spontaneously return to erect, even-surfaced condition after the stroke.

3. A golfer's driving mat comprising a facing composed of a flexible base surfaced with bristle wires upstanding free of lateral support above said base, and resiliently flexible relative thereto, so that they yield laterally under a golf club 75

stroke at a missile on the mat, and a resiliently yielding layer or pad of elastic sponge rubber under said base backing said facing, all so that while said facing yields resiliently downward 5 under a golf club stroke at a missile on the mat, the bristle wires and facing spontaneously return to erect, even-surfaced condition after the stroke.

4. A golfer's driving mat comprising a structural back, a resiliently yielding elastic pad on said back secured to its surface, and a facing on 10 said pad comprising a flexible base secured to

the surface of the pad and itself surfaced with upstanding bristle wires resiliently flexible relative to said base.

5. A golfer's driving mat comprising a facing composed of a flexible base surfaced with upstanding bristle wires resiliently flexible relative to said base, a resiliently yielding elastic pad under said base, and a frame enclosing the edges of said facing and pad, and at one side overhanging the facing bristles and beveled outward 10 and downward.
